ARC TUBE MOUNT

Paul A. Dell, Highland Heights, Ohio, assignor to General Electric Company, a corporation of New York

Application September 12, 1951, Serial No. 246,231

5 Claims. (Cl. 313—27)

The present invention relates to high pressure electric discharge lamps having an inner arc tube of vitreous material, an outer vitreous envelope and a mount supporting said tube in said envelope.

Heretofore such lamps have been made with beaded inleads wires extending from rounded or tapered ends of the arc tube and the support for the arc tube has engaged the hot tube inwardly from the inleads. Such structure, due to the high operating temperature of the arc tube, has presented difficulties in supporting the tube without conducting too much heat away from it through the supports, in avoiding electrolysis of the vitreous tube material by the electrically charged support members engaging the tube, and in avoiding thermal shock of sufficient magnitude to cause cracking of the tube.

Recently vitreous arc tubes having an externally extending pinched seal at each end of the tube have been made commercially available by the assignee of the present application and the principal object of the present invention is to provide a support for an arc tube of this kind which avoids the difficulties characteristic of prior supports and which is of simple, rugged structure providing support members having sufficient flexibility for the expansion and contraction of the component parts of the lamp without breaking the vitreous arc tube supported thereby. Still further objects and advantages of the invention will be apparent from the following detailed description of species thereof and from the appended claims.

In the drawing accompanying and forming part of this specification species of the invention are shown in which, Fig. 1 is a perspective view of a discharge lamp of the high pressure type in which the mount for the inner arc tube embodies the present invention; Fig. 2 is a similar view on an enlarged scale of the arc tube engaging member of the mount shown in Fig. 1; Fig. 3 is a similar view of another species of arc tube engaging member embodying the invention, and Fig. 4 is a similar view of still another arc tube engaging member embodying the invention.

Referring to Fig. 1 of the drawing the lamp comprises an outer vitreous envelope 1 having a re-entrant stem 2 through the pinch 3 of which extend the leading-in wires 4 and 5 which are connected at their outer ends to the contacts on the usual screw type base 6 of the lamp and terminate within the outer envelope for connection to the terminals of the inner arc tube 7.

The inner arc tube 7 is made of hard vitreous material, such as quartz, and has sealed therein at opposite ends thereof a pair of main discharge supporting electrodes 8 and 9 the inleads 11 and 12 of which constitute the arc tube terminals. An auxiliary starting electrode 10 is sealed into one end of the tube 7 adjacent the main electrode 8. The current inlead wires 11, 12 and 13 for said electrodes 8, 9 and 10, respectively, have a thin flattened section hermetically united with the pinched end tube portions 14 and 15 extending outwardly from the arc tube 7 as described and claimed in my copend-

ing joint application with Edward B. Noel, Serial No. 244,818, filed September 1, 1951, titled "Ribbon Lead Construction," now Patent No. 2,667,595, patented January 26, 1954, and assigned to the assignee of this application. The arc tube 7 has a filling of starting gas, such as argon at a pressure of 2 to 3 millimeters, and a measured quantity of mercury sufficient to produce a high pressure, unsaturated vapor atmosphere at the operating temperature of the arc tube 7.

10 The mount for the arc tube 7 within the outer envelope 1 comprises a harness made up of a U-shaped stiff metal wire having its bent center portion 16 welded to the inlead 4 of stem 2 and its parallel legs 17 and 18 extending longitudinally of the arc tube 7 and terminating at the opposite end of the outer envelope 1. A pair of spring members 19 and 20 press against the envelope 1 and are welded to the free ends of the legs 17 and 18, respectively, and a spreader member 21 is similarly attached to and between the free ends of the legs as shown. The U-shaped support is thus firmly held in position in the envelope 1.

The arc tube 7 is attached to the U-shaped support by transverse metal channel members 22 and 23 welded to the legs 17 and 18 of the U-shaped support and engaging the outer ends of the pinched portions 14 and 15 of the tube 7. The channel supports 22 and 23 are of the same structure and are provided with tabs 24 (Fig. 2) bent inwardly into the channel and welded to the legs 17 and 18 of the wire support. The central portion or web of each of the channel supports 22 and 23 is cut and shaped to provide an elongated opening for receiving a flat pinch part of the tube 7 and a pair of rounded resilient fingers 25 and 26. The fingers 25 and 26 engage the outer corners of the pinch parts 14 and 15 of the arc tube 7, as best shown in Fig. 2, in which pinch part 14 and the inleads 11 and 13 are shown in broken lines. The channel supports 22 and 23 are so spaced on the legs 17 and 18 of the U-shaped support that the arc tube 7 is held firmly therebetween.

40 The arc tube 7 is held firmly but flexibly in proper position in the outer envelope 1 by the mount and no part of the latter touches the hot portion of the arc tube 7 surrounding the electrodes and the discharge path therebetween. The difficulties characteristic of prior mounts and pointed out above are thus completely avoided by the different structure of the present mount.

The transverse support members shown in Figs. 3 and 4 of the drawing are useful in the mount shown in Fig. 1 and are similar to the member shown in Fig. 2 and described above except in the embodiment of Fig. 3 the fingers are flat rather than rounded in cross section and have a cut-out portion to provide an opening 27 to receive a side of the press 14. Also the fingers are bent laterally to provide an upwardly extending end 28 fitting and hooking over an outer corner of the press 14 and an angularly disposed portion 29 joining the end 28 to the bottom of the channel-shaped member 22. The support member of Fig. 3 like that of Fig. 1 provides a firm but sufficiently flexible support to permit expansion and contraction of the metal and glass lamp components at different rates during service without injury to the arc tube 7.

In the embodiment of Fig. 4 of the drawing the fingers 30 and 31 are bent outwardly from the interior of the channel and the member 22 is so mounted on the legs 17 and 18 that the fingers 30 and 31 extend generally in the direction of the arc tube and engage the body portion of the press 14. The ends of the fingers 30 and 31 are notched as shown at 32 and 33 to loosely engage similarly notched portions of the press 14.

The electrical connections between the electrodes 8, 9

and 10 and the current inleads 4 and 5 connected with contacts on the base 6 of the lamp shown in Fig. 1 are made in the conventional manner. Main electrode 9 is connected through its inlead 12 and the flexible conductor 35 to the leg 17 of the U-shaped mount, the center portion 16 of which is welded to the inner end of current lead 4. The main electrode 8 is connected through its inlead 11 and a flexible conductor 36 to the inlead 5. The said conductor 36 passes through an opening in the metal heat shield 37 secured to the legs 17 and 18 of the U-shaped mount and is electrically insulated from said shield by the glass tube 38. The auxiliary electrode 10 is electrically connected to the main electrode 9 through its inlead 13, the flexible conductor 39, the resistor 40 and the stiff conductor 41 welded to the portion 16 of the U-shaped support member. The flexible conductor 39 also passes through the opening in the heat shield 27 and is electrically insulated from said shield by the glass tube 42.

What I claim as new and desire to secure by Letters Patent of the United States is:

1. An electric discharge lamp of the high pressure type comprising in combination, a vitreous arc tube having at each end an external flat press portion carrying an electric terminal, an outer envelope enclosing said arc tube, and a mount supporting said tube in fixed position within said envelope, said mount comprising a U-shaped stiff metal wire support attached to said envelope and narrow, spaced transverse metal members attached to the legs of said support and supporting said arc tube therebetween, each of said narrow transverse members having an elongated central opening accommodating a press portion of said arc tube with the sides of said opening engaging said press portion to limit lateral movement of said arc tube in said envelope, each of said transverse support members comprising also integral spring fingers extending from the ends of said opening into engagement with the said accommodated press portion, the said fingers on said transverse support members resiliently holding said arc tube against longitudinal displacements in said envelope and with the tubular portion of said arc tube spaced from said transverse support members to minimize heat losses from said arc tube through said mount.

2. An electric discharge lamp of the high pressure type comprising in combination, a vitreous arc tube having at each end an external flat press portion carrying an elec-

tric terminal, an outer envelope enclosing said arc tube, and a mount supporting said tube in fixed position within said envelope, said mount comprising a U-shaped stiff metal wire support and narrow, spaced transverse metal members attached to the legs of said support and supporting said arc tube therebetween, each of said transverse support members being shaped as a channel having upstanding sides spaced apart a distance slightly greater than the thickness of the flat press portions of the arc tube and having an elongated central opening in its web accommodating a press portion of said tube the sides of which engage the said press portion to limit lateral displacements of said tube in said envelope, each of said transverse support members having also integral spring fingers extending from the ends of said opening into engagement with the said accommodated press portion, the said fingers on said transverse support members resiliently holding said arc tube against longitudinal displacements in said envelope and with the tubular portion of said arc tube spaced from said transverse support members to minimize heat losses from said arc tube through said mount.

3. An electric discharge lamp as in claim 2 wherein the spring fingers are bent inward into the channel-shaped member and engage the corners of said press.

4. An electric discharge lamp as in claim 2 wherein the spring fingers are bent inward into the channel-shaped member and are provided with openings so as to hook over the corners of said press.

5. An electric discharge lamp as in claim 2 wherein the spring fingers are bent outward and engage the sides of said press.
